[57] **CLAIM**

The ornamental design for a socket connector with ribbed towers, as shown and described.

DESCRIPTION

FIG. 1 is a perspective view of the socket connector with ribbed towers.

FIG. 2 is a top plan view of the socket connector with ribbed towers.

FIG. 3 is a bottom plan view of the socket connector with ribbed towers.

FIG. 4 is a right side elevational view of the socket connector with ribbed towers.

FIG. 5 is a left side elevational view of the socket connector with ribbed towers.

FIG. 6 is a front elevational view of the socket connector with ribbed towers; and,

FIG. 7 is a rear elevational view of the socket connector with ribbed towers.

The broken line showing throughout the drawing figures is included for the purpose of illustrating environmental structure only and forms no part of the claimed design.
